Design No 483.

James L. Jackson.

Design for a cradle-frame, summer piece of furniture.

Patented August 10, 1852.

Des. 483

James L. Jackson of New York, N.Y.
Letters Patent No. 483 Dated Aug 10th 1852

The schedule referred to in these Letters Patent and making part of the same

Dec. 483

To all whom it may concern:

Be it known that I, James G. Jackson, of the City, County & State of New York, have invented or produced, a new and original design for a Grate-frame, Summer piece and box fender, and I do hereby declare the following to be full clear and exact description of the same reference being had to the accompanying drawing making a part thereof, and which represents one half of the ornamental design in full, and the other half, which is precisely similar in outline only.

The frame is rectangular, and the outer margin is bordered by a delicate double moulding a, and the inner margin which has perpendicular sides and a semi-elliptical top, has a single moulding b, extending entirely around it, and outside of this is a wide cavetto moulding c, over which projects highly wrought arabesque flowers d, the crown and side pieces being separated by plain mouldings e. Outside of these ornaments is a plain ground f, flanked by a raised bead g, from which project over said plain ground, volutes h, connected by brackets i, nearly lost under the bead g. Around this is a delicate cavetto k, and Gothic beading l. The corners of the frame are ornamented with a cyma, made up of a nose for a centre piece, from which extends running vines carrying flowers, buds and foliage, and terminating in the extreme corners of the angular shaped panel. The shaded line x x, represents the outline of a cross section through the frame.

The summer piece has a shield m, in its centre from which extends out open lace work n, which terminates in brackets o, at the four sides, and volutes p, at the corners. Outside of this is a cavetto moulding q, which throws out the outer part of the summer piece in strong relief. The bottom of the summer piece has for a centre a highly wrought arabesque figure r, from the sides of which projects lattice work s, terminating in flowered volutes, entwining a stem t, which extends around the frame and embraces at the top, a top centre arabesque piece u. The stems, at their lower ends are finished with pendants w.

The fender is of the kind known as "box fenders," the top of which is ornamented with radial lines y. The top edge is a convex moulding wrought in arabesque and open work, and around the outer side

of the fender is rosette open work a. on a double reversed ground, and the bottom edge is finished with small beading, and scalloped edges, and the whole rests upon the feet b.

Having thus fully described and represented the nature of my design, what I claim herein as new and desire to secure by Letters Patent, is the combination and arrangement of the ornamental figures herein represented and forming an ornamental design for a grate frame, summerpiece and box fender.
